SPECIMEN HOLDER ASSEMBLY

James Hillier, Cranbury, N. J., assignor to Radio Corporation of America, a corporation of Delaware

Application March 1, 1945, Serial No. 580,406

7 Claims. (Cl. 250—49.5)

1

The present invention relates to electron microscopes and more particularly to an improvement in specimen holders.

Some of the objects of the present invention are to provide an improved specimen holder; to provide a novel stage and specimen holder assembly; to provide a mounting for a specimen holder wherein provision is made for tilting the specimen holder to obtain stereoscopic effects; to provide a readily demountable specimen holder; to provide a specimen chamber, specimen holder, and stage assembly wherein the holder is readily accessible for changing specimens or adjusting to a selected position with reference to the axis of the column; to provide means whereby a specimen holder can be swung about its longitudinal axis through a predetermined angle to permit portions of the front and one side of the specimen to be viewed or photographed; and to provide other improvements as will hereinafter appear.

In the accompanying drawings:

Figure 1 represents a transverse section of the object or specimen chamber of an electron microscope showing a specimen holder and stage assembly embodying one form of the present invention;

Figure 2 represents a front elevation of the specimen holder;

Figure 3 represents a side elevation of the specimen holder;

Figure 4 represents an end elevation of the specimen holder viewed from the right of Fig. 3;

Figure 5 represents a section on line 5—5 of Fig. 2; and

Figure 6 represents a sectional detail on an enlarged scale of the end of the specimen holder in the specimen holder of Fig. 1.

Referring to the drawings, one form of the specimen holder of the invention comprises two elongated members 10 and 11, the former having a convex arcuate groove 12 extending lengthwise at the rear thereof, and the latter having a concave arcuate face 13 extending lengthwise at the front thereof, said groove 12 and face 13 being complementally arcuate whereby the member 10 which carries the clip 14 for mounting the specimen unit can be turned about its longitudinal axis and move freely relative to the member 11. The two members 10 and 11 are held in contact by a biasing spring 15 stretched between a pin 16 and a fixed lug 17. The front face of the member 10 is notched transversely to seat the pin 16 and apertures 18 and 20 are provided in the respective members 10 and 11 for conveniently bringing the spring 15 to its attaching position with the

2

lug 17. The lug 17 is formed as a part of a base 21 which serves as a mount for the member 11, and is attached thereto by screws 22. A friction spring 23 is also held by the screws 22 and lies along the outer face of the base 21 in order to react against the juxtaposed face of the stage 24.

For removably mounting the specimen holder on the stage 24, the base 21 is so dimensioned as to project at each side of the member 11 in order to fit within and have sliding relation within a way formed by two parallel undercut rails 25, preferably formed integral with the stage 24. The depth of the way is such as to receive the thickness of the base 21 plus the friction spring 23 when under compression. Thus, when the specimen holder is guided into operative position, the spring pressure acts as a rigid holding means to prevent holder displacement when the specimen is under observation. When thus fixed in position, the through hole 26, which directs the electron beam upon the specimen, is located coaxially with respect to the column of the microscope and to the hole 19 in the stage 24. It should be noted that the axis of rotation of the specimen holder is at right angles to the axis of the column as well as to the electron beam, an important feature in that it not only properly locates the object or specimen plane transversely of the beam but brings the holder to a readily accessible position.

For maintaining the portions of the through hole 26, which are respectively in the member 10, the member 11, and the base 21, in alinement, a pin 27 is fixed to the base 21 and to the member 11 in order to project and ride within a slot 28, transversely cut in the rear face of the member 10. Thus, the member 10 can be angularly turned without disturbing the alined through hole relation of the parts. Furthermore, it should be noted that the base 21 projects at its lower end in order to seat upon shoulders 30 formed as a part of the stage 24 to thereby serve as a means which ensures the accurate coaxial alinement of the specimen holder hole and the axis of the column so that the electron beam passes through the center of the plane of the specimen.

As a means to indicate the angular relation between the members 10 and 11, a pointer 31 projects laterally from the member 10 beyond the upper end of both the member 11 and base 21 and is in a location for ready observation when the closure 32 over the access opening 33 leading to the specimen chamber 34 of the microscope is removed. Stops 35 straddle the pointer 31 in spaced relation to form limits of angular movement and are here shown as part of the lug 17.

In Fig. 1 the lens unit 36 and electron gun unit 37 are fragmentarily indicated to illustrate the general assembly with which the specimen holder of the invention is associated.

For normal or symmetrical viewing of the specimen, the pointer 31 is located in mid-position, but for stereoscopic viewing the pointer 31 is turned through the desired angle in either direction and thus the specimen can be viewed or photographed at a selected angle to one side of the center position and then at the corresponding angle at the opposite side of the center position.

By the present novel construction, very accurate adjustment of the specimen holder can be obtained both for direct and stereoscopic viewing, and since the pointer end of the holder is in close proximity to the access opening 33 it can be quickly reached by removing the closure 32 which is normally sealed under atmospheric pressure. It should also be noted that the specimen holder is mounted radially of the stage so that the sliding connection allows the holder to be readily withdrawn for specimen replacement. This construction obviates the difficulty attendant to the replacement of specimen holders which are disposed coaxially of the electron beam.

I claim as my invention:

1. A specimen holder for electron microscopes consisting of an elongated member arranged to be fixed and having an arcuate groove extending lengthwise thereof, a second member having an arcuate groove complementary to the arcuate face of said fixed member and arranged to turn about the axis of said groove, means for mounting a specimen on said movable member with the plane of the specimen coincident with said axis, and means permitting turning of said movable member relative to said fixed member while maintaining said arcuate groove and face in contact.

2. A specimen holder for electron microscopes consisting of an elongated member arranged to be fixed and having an arcuate groove extending lengthwise thereof, a second member having an arcuate face complementary to the arcuate groove of said fixed member and arranged to turn about the axis of said groove, means for mounting a specimen on said movable member with the plane of the specimen coincident with said axis, and biasing means holding said arcuate groove and face together.

3. A specimen holder for electron microscopes consisting of an elongated member arranged to be fixed and having an arcuate groove extending lengthwise thereof, a second member having an arcuate face complementary to the arcuate groove of said fixed member and arranged to turn about the axis of said groove, means for mounting a specimen on said movable member with the plane of the specimen coincident with said axis, means permitting turning of said movable member relative to said fixed member while maintaining said arcuate groove and face in contact, and means

to limit the turning movement of said movable member.

4. In an electron microscope of the type having a column with its axis alined with the beam of an electron gun, the combination of a stage having an opening coaxial with said axis, and a specimen holder mounted to slide radially of said stage and normally positioning a specimen in register with said stage opening, said holder including two arcuate contacting faces for angularly varying the plane of said specimen with respect to said electron beam.

5. In an electron microscope of the type having a column with its axis alined with the beam of an electron gun, the combination of a stage having an opening coaxial with said axis, a specimen holder including a member arranged to turn about an axis perpendicular to said electron beam in assembled position, means for mounting a specimen on said member with its plane coincident with said member axis, said holder locating said specimen in register with said stage opening, and means for removably mounting said holder in juxtaposed relation to said stage.

6. In an electron microscope of the type having a column with its axis alined with the beam of an electron gun, the combination of a casing forming a specimen chamber, a specimen holder including a member arranged to turn relatively, means for removably mounting said holder in said casing with the turning axis of said member perpendicular to said electron beam, and means for mounting a specimen on said turnable member with its plane coincident with member axis.

7. In an electron microscope of the type having a column with its axis coaxial with the beam of an electron gun, the combination of a casing forming a specimen chamber, a stage in said chamber having an opening alined with said axis and a pair of undercut ribs forming a way radially of said stage, a base arranged to slide in said way, a member fixed to said base having an arcuate groove extending longitudinally thereof, a second member having an arcuate face complementary to said fixed member groove, means maintaining said groove and face in contact but permitting said second member to turn about an axis parallel to said stage way, and means mounting a specimen on said movable member in a plane perpendicular to and intercepting said electron beam but coincident with said member axis.
